(57) **CLAIM**

The ornamental design for a wristband with an insertable sleeve for electronic paper display, as shown and described.

DESCRIPTION

FIG. 1 is a front perspective view of the invention.

FIG. 2 is a rear perspective view of the invention.

FIG. 3 is a top plan view of the invention.

FIG. 4 is a bottom plan view of the invention.

FIG. 5 is a front elevational view of the invention.

FIG. 6 is a rear elevational view of the invention.

FIG. 7 is a right side view of the invention.

FIG. 8 is a left side view of the invention.

FIG. 9 is a top perspective view of the invention with the electronic paper display cover partially open and an unclaimed electronic paper partially inserted within the insertable sleeve; and,

FIG. 10 shows the invention in use.

The broken lines shown in FIGS. 9 and 10 depict an electronic paper and a wearer of the invention respectively and form no part of the claimed design.
